UNITED STATES PATENT OFFICE

ANDRE J. MEYER, OF DETROIT, MICHIGAN, ASSIGNOR TO CONTINENTAL MOTORS CORPORATION, OF DETROIT, MICHIGAN, A CORPORATION OF VIRGINIA

INTERNAL-COMBUSTION ENGINE

Application filed January 3, 1928. Serial No. 244,062.

This invention relates to internal combustion engines and refers more particularly to the single sleeve valve type of engine commonly known as the "Burt-McCollum" generally illustrated for example in the patent to Burt No. 1,310,646. In this type of engine a single sleeve valve has a combined reciprocating and oscillating movement with respect to the cylinder axis, the sleeve valve and cylinder having cooperating intake and exhaust ports, a point on the sleeve tracing a closed curve path with respect to the cylinder wall.

My invention refers particularly to the ports of the sleeve and cylinder, one object being to provide a construction affording a more efficient port operation. A further feature of my invention resides in a sleeve valve port and cylinder port cooperating therewith, said ports providing an increased opening for a given valve travel and timing whereby greater engine efficiency and generally improved performance is obtained. My port construction is especially advantageous in connection with the sleeve and cylinder intake ports, where it is desirable to quickly open the ports to a full open position followed by a quick closing action toward the completion of the intake event of the engine cycle. By reason of my port construction both the intake and exhaust ports are quickly opened and closed at the proper time in the engine cycle, the cylinder intake gases and the exhaust gases being very efficiently introduced and exhausted respectively.

Further features of my invention reside in the novel combination of parts and structural details hereinafter described and claimed.

In the accompanying drawings,

Fig. 1 is a detail sectional view through a typical cylinder of the engine,

Fig. 2 is a detail view illustrating the construction of one of the sleeve ports and cooperating cylinder ports,

Fig. 3 is a development of the sleeve and cylinder showing the ports thereof and illustrating a slightly modified form of my invention,

Fig. 4 is a detail view illustrating the con-

struction of one of the sleeve ports and cooperating cylinder port of the type shown in Fig. 3,

Fig. 5 is a view corresponding to Figs. 2 and 4 illustrating a still further modification of my invention, and

Fig. 6 is a diagram showing port opening area against crankshaft angle for the different embodiments of my invention.

Referring to the drawings, reference character A represents the engine usually of the multi-cylinder type, one of the cylinders 10 having intake and exhaust ports 16 and 10^a respectively, the cylinder being closed by the usual cylinder head 11 having a water jacket portion 12 depending within the cylinder and spaced therefrom to provide a sleeve pocket 13 accommodating the movement of the single sleeve valve 14. The piston 15 is customarily located generally as illustrated, 60 within the sleeve valve.

Referring to Fig. 2 I have illustrated my improved port construction, one of the sleeve valve intake and cylinder ports being shown. The cylinder intake port is indicated by the full line 16 and the associated sleeve intake port by the full line 17. As is well known in the art for this general type of sleeve valve, the sleeve is driven in various ways by some means moving generally in a circular path 18 depending on the desired sleeve travel. Because of the oscillating component of the sleeve valve, the movement actually imparted to the sleeve is more generally elliptical as at 19, any point on the sleeve moving in such a closed curve path with respect to the associated cylinder. Depending on the particular driving mechanism employed the ellipse 19 and circle 18

may approach each other or diverge to a greater or lesser extent, and I do not limit my invention to any particular figure either symmetrical or non-symmetrical traced on the cylinder by a point on the sleeve except that any point on the sleeve under the influence of the combined reciprocating and oscillating movement will always trace a closed curve path with respect to the cylinder which path according to the present practice is most frequently elliptical. In the illustration in 80 85 90 95 100

Fig. 2 the sleeve has a vertical travel from 20 to 21 and a lateral or oscillatory travel from 22 to 23. Assuming that it is desired to obtain intake closing 42° beyond bottom dead center of the engine crank, the angle 24 would be 21° , it being usual in a four stroke cycle engine to operate the sleeve valve at half engine crankshaft speed. For a two stroke cycle engine the sleeve valve drive-shaft and crankshaft would operate at equal angular velocities, this being readily understood by one skilled in the art. From the angle 24 a point 25 is obtained on the circle 18 which becomes 26 with reference to the sleeve valve travel. From a standpoint of manufacture it is desirable to cut the ports usually by punching or more generally by a rotary cutter. Such a cutter may have a minimum radius 27 so that with such considerations in mind in constructing the ports, I describe an arc 27^a of such radius from the point 26. The usual type of ports is shown by the dotted line 28 for the sleeve intake port and 29 for the associated cylinder intake port, my port construction deviating therefrom by inclining the bottom edge 30 of the sleeve port and the cooperating top edge 31 of the cylinder port. The edge 31 is tangent to the arc 27^a which determines the lower limit of this edge, i. e., the lower limit of the closing edge of the cylinder intake port is determined by the desired angle or time of intake closing. The dot and dash figures 30^a, 30^b, 30^c, and 30^d illustrate successive positions of the sleeve port 17 any point of which moves in a path similar to 19. The position 30^c is substantially the position at the time of cylinder mixture explosion or maximum cylinder pressure and the upper limit of the edge 31, determining the inclination of this edge, is based on the minimum sealing required under the particular circumstances of the engine. At this period of the engine cycle the sleeve port 17 is located above the cylinder port 16 within the sleeve pocket 13 and it is apparent that a certain amount of seal must be provided at this time to prevent escape of the expanding gases through the sleeve and cylinder ports. Where a sealing ring 32 is employed in the cylinder head it is ordinarily sufficient to allow a sealing space between port 16 and port position 30^c substantially equal to the distance from the bottom of the cylinder head 12 to the top of the sealing ring 32. It is not entirely necessary to use such a sealing ring as it is found in many instances that ample seal may be obtained by the engagement of the sleeve valve with the cylinder and cylinder head walls. In either event the upper limit of the cylinder port edge 31 is determined preferably by the minimum amount of sealing required when the associated sleeve port 17 is in the position 30^c corresponding substantially to maximum cylinder pressure conditions. The radius 27

is employed at all corners of the cylinder and sleeve ports facilitating quantity manufacture of these ports, it being understood that sharp corners may be employed if desired, especially where the ports are punched. I have discovered that by providing ports according to my invention, considerably greater intake and exhaust opening is obtained. This may be illustrated by Fig. 6 where the area of port opening is plotted against the crankshaft angle. In this Fig. 33 represents a typical curve for the conventional ports 28, 29, while 34 represents a typical curve for the ports 16, 17 embodying my invention. The differences in these curves is the accumulated gain in port opening for the same valve travel. In order to more clearly illustrate the gain in port opening I have illustrated the sleeve port position 30^a compared with the same position of the conventional sleeve port 28^a, the shaded designated areas representing the gain and loss at this position. It is readily apparent that the area designated "gain" is greater than that designated "loss" affording a net gain. The accumulated net gain over the whole intake period is illustrated by the difference between the curves 34 and 33 of Fig. 6.

In the sleeve port position 30^a the cylinder pressure has greatly fallen off, exhaust ordinarily taking place, so that the amount of seal between the sleeve and cylinder intake ports indicated at 35 may be considerably less than with the sleeve port in the position of firing.

In the embodiment illustrated in Fig. 2 the opening edges 36, 37, of the sleeve and cylinder ports respectively are straight lines, the same being true for the respective closing edges of these ports which, as described hereinbefore, are inclined with respect to a plane perpendicular to the cylinder or sleeve axis.

It will be understood that where manufacturing or other conditions permit or make desirable a sleeve and cylinder port embodying my invention but eliminating or reducing the rounded corners of radius 27 then the point 26 becomes or approaches the lower limit of the closing edges of the sleeve and cylinder ports so as to afford the proper valve closing.

For the purpose of illustrating my invention I have shown in Fig. 2 a typical sleeve and cylinder intake port, the exhaust ports being preferably of similar construction, with the exception that the inclined edges become exhaust opening edges as will be apparent from Fig. 3.

Referring to Figs. 3 and 4 I have illustrated a modified embodiment of my invention differing only from Fig. 2 in the opening edges of the sleeve and cylinder intake ports and the closing edges of the sleeve and cylinder exhaust ports. These edges are of the sinuous form such as generally illustrated in the Burt

5 patent referred to hereinbefore, the edges of the sleeve and cylinder intake ports being shown in Fig. 4 at 39 and 40 respectively. In this figure the sleeve intake port 41 is at the opening position with respect to the cylinder intake port 42. The successive sleeve port positions, corresponding to those described in connection with Fig. 2 are indicated at 41^a, 41^b, 41^c, and 41^d. The remainder 10 of the port construction corresponds with Fig. 2 and the shaded areas indicated by "gain" and "loss" illustrate a net gain for a typical sleeve port position 41^a with respect to a conventional port 28^a. In Fig. 4 the net 15 gain derived by my invention in combination with the sinuous edges 39, 40 is indicated in Fig. 6 by the difference between curves 43 and 33, the port shown in Fig. 4 giving greater intake opening area for the same timing 20 and sleeve travel than the port shown in Fig. 2.

In Fig. 3 I have illustrated a typical development of the sleeve and cylinder ports of the type illustrated in Fig. 4, it being 25 readily understood that the other embodiments of my inventions, such as illustrated in Fig. 2 and Fig. 5, will have a development substantially corresponding to Fig. 3. In Fig. 3 the cylinder ports are shaded, the intake ports being indicated by "Int." and the exhaust ports by "Exh." If desired a double purpose port 43^a may be incorporated, serving both as a sleeve intake and exhaust port, the intake closing edge 44 and exhaust opening edge 30 converging.

While ports having a sinuous edge are disclosed in the Burt patent aforesaid, and while the advantages thereof are well known, my invention provides still further advantages 40 due to the increased length of the sinuous edges 39, 40, the top points of these edges lying above the conventional edge 29 as will be apparent from Fig. 4.

Referring now to Fig. 5 I have illustrated 45 a still further port construction in a modified form but embodying my invention. In this form the sleeve and cylinder intake opening edges may be of the form illustrated in either Fig. 2 or Fig. 4, the latter type being shown. Positions of the sleeve intake port 45 with 50 respect to the cylinder intake port 46 are respectively shown at 45^a, 45^b, 45^c and 45^d, generally corresponding with Figs. 2 and 4, and for convenience of illustration and comparison all of the embodiments are illustrated 55 as having the same assumed valve travel and timing conditions.

In Fig. 5 the closing edges 47, 48 of the sleeve and cylinder intake ports are not inclined between the lower and upper limits determined as before, these edges being formed with longitudinal spaced and laterally offset horizontal edge portions 49, 50, connected by a generally longitudinally or 60 vertically extending line 51. I have dis-

covered that such a construction affords a still greater intake opening area for a given valve travel and timing, the curve 52 of Fig. 6 illustrating the opening area in comparison with curves 33, 34 and 43.

70 Each of the illustrated embodiments of my invention shows a sleeve and cooperating cylinder intake port whose cooperating closing edges deviate from a straight line which may be conveniently referred to as lateral, horizontal, or parallel with a plane perpendicular to the sleeve or cylinder axis. In each instance the closing edges have one end lower vertically than the other, the lower end being determined by the desired timing conditions for intake closing and the upper end being determined by the conditions of sealing required between the cooperating sleeve and cylinder ports when substantially maximum pressure conditions exist in the engine cylinder. The upper and lower ends of these cooperating closing edges are connected by a line or edge which may deviate if desired from that illustrated at 30, 31 in Figs. 2 and 4, or at 49, 50 in Fig. 5.

75 Throughout the specification and claims such terms as vertical, longitudinal, height, horizontal, etc., refer for convenience to an assumed vertical position of a typical engine cylinder and sleeve valve axis.

80 What I claim as my invention is:

1. An internal combustion engine comprising 85 a cylinder having intake and exhaust ports, a piston reciprocating within the cylinder, a single sleeve valve coaxial with the cylinder and having a combined reciprocating and oscillating movement with respect to the sleeve and cylinder axes, said sleeve having intake and exhaust ports cooperating with the respective cylinder ports, said cylinder intake port having a closing edge the ends of which are spaced longitudinally with respect to the cylinder axis. 100

2. An internal combustion engine comprising 105 a cylinder having intake and exhaust ports, a piston reciprocating within the cylinder, a single sleeve valve coaxial with the cylinder and having a combined reciprocating and oscillating movement with respect to the sleeve and cylinder axes, said sleeve having intake and exhaust ports cooperating with the respective cylinder ports, said cylinder intake port having a closing edge the ends of which are spaced longitudinally with respect to the cylinder axis, the cooperating intake port of the sleeve having a closing edge the ends of which are spaced longitudinally with respect to the sleeve axis. 115

3. An internal combustion engine comprising 120 a cylinder having intake and exhaust ports, a piston reciprocating within the cylinder, a single sleeve valve coaxial with the cylinder and having a combined reciprocating and oscillating movement with respect to the sleeve and cylinder axes, said sleeve having 125

- intake and exhaust ports cooperating with the respective cylinder ports, said cylinder intake port having a closing edge the ends of which are spaced longitudinally with respect to the cylinder axis, the cooperating intake port of the sleeve having a closing edge the ends of which are spaced longitudinally with respect to the sleeve axis, the spacing of the respective ends of the sleeve and cylinder intake port closing edges being substantially equal. 5

4. An internal combustion engine comprising a cylinder having intake and exhaust ports, a piston reciprocating within the cylinder, a single sleeve valve coaxial with the cylinder and having a combined reciprocating and oscillating movement with respect to the sleeve and cylinder axes, said sleeve having intake and exhaust ports cooperating with the respective cylinder ports, said sleeve intake port having a closing edge the ends of which are spaced longitudinally with respect to the sleeve axis. 10

5. An internal combustion engine comprising a cylinder having intake and exhaust ports, a piston reciprocating within the cylinder, a single sleeve valve coaxial with the cylinder and having a combined reciprocating and oscillating movement with respect to the sleeve and cylinder axes, said sleeve having intake and exhaust ports cooperating with the respective cylinder ports, said cylinder intake port having a closing edge one end of which is lower than the other with respect to the cylinder axis. 15

- tudinally with respect to the sleeve axis, the spacing of the respective ends of the sleeve and cylinder exhaust port opening edges being substantially equal.
- 5 12. An internal combustion engine comprising a cylinder having intake and exhaust ports, a piston reciprocating within the cylinder, a single sleeve valve coaxial with the cylinder and having a combined reciprocating and oscillating movement with respect to the sleeve and cylinder axes, said sleeve having intake and exhaust ports cooperating with the respective cylinder ports, said cylinder and sleeve intake ports having cooperating closing edges the ends of which are spaced longitudinally of the cylinder and sleeve axes respectively. 70
- 10 13. An internal combustion engine comprising a cylinder having intake and exhaust ports, a piston reciprocating within the cylinder, a single sleeve valve coaxial with the cylinder and having a combined reciprocating and oscillating movement with respect to the sleeve and cylinder axes, said sleeve having intake and exhaust ports cooperating with the respective cylinder ports, said cylinder intake port having a closing edge extending at an angle to a plane perpendicular with the cylinder axis, said sleeve intake port having a closing edge extending at an angle to a plane perpendicular with the sleeve axis, said cylinder and sleeve intake ports having cooperating sinuous opening edges. 75
- 15 14. An internal combustion engine comprising a cylinder having intake and exhaust ports, a piston reciprocating within the cylinder, a single sleeve valve coaxial with the cylinder and having a combined reciprocating and oscillating movement with respect to the sleeve and cylinder axes, said sleeve having intake and exhaust ports cooperating with the respective cylinder ports, said sleeve intake port having a closing edge extending at an angle to a plane perpendicular with the sleeve axis. 80
- 20 15. An internal combustion engine comprising a cylinder having intake and exhaust ports, a piston reciprocating within the cylinder, a single sleeve valve coaxial with the cylinder and having a combined reciprocating and oscillating movement with respect to the sleeve and cylinder axes, said sleeve having intake and exhaust ports cooperating with the respective cylinder ports, said cylinder intake port having opening and closing edges respectively inclined with respect to the cylinder axis and a plane perpendicular to the cylinder axis, said sleeve intake port having opening and closing edges respectively inclined substantially the same as the cylinder intake port inclined edges. 85
- 25 16. An internal combustion engine comprising a cylinder having intake and exhaust ports, a piston reciprocating within the cylinder, a single sleeve valve coaxial with the cylinder and having a combined reciprocating and oscillating movement with respect to the sleeve and cylinder axes, said sleeve having intake and exhaust ports cooperating with the respective cylinder ports, said cylinder intake port having a closing edge the ends of which are spaced longitudinally with respect to the cylinder axis, the cooperating intake port of the sleeve having a closing edge the ends of which are spaced longitudinally with respect to the sleeve axis, the cooperating opening edges of the cylinder and sleeve intake ports being sinuous. 90
- 30 17. An internal combustion engine comprising a cylinder having intake and exhaust ports, a piston reciprocating within the cylinder, a single sleeve valve coaxial with the cylinder and having a combined reciprocating and oscillating movement with respect to the sleeve and cylinder axes, said sleeve having intake and exhaust ports cooperating with the respective cylinder ports, said cylinder intake port having a closing edge extending at an angle to a plane perpendicular with the cylinder axis, said sleeve intake port having a closing edge extending at an angle to a plane perpendicular with the sleeve axis, said cylinder and sleeve intake ports having cooperating sinuous opening edges. 95
- 35 18. An internal combustion engine comprising a cylinder having intake and exhaust ports, a piston reciprocating within the cylinder, a single sleeve valve coaxial with the cylinder and having a combined reciprocating and oscillating movement with respect to the sleeve and cylinder axes, said sleeve having intake and exhaust ports cooperating with the respective cylinder ports, said cylinder intake port having a closing edge formed of connected longitudinally spaced and laterally offset substantially horizontal edge portions. 100
- 40 19. An internal combustion engine comprising a cylinder having intake and exhaust ports, a piston reciprocating within the cylinder, a single sleeve valve coaxial with the cylinder and having a combined reciprocating and oscillating movement with respect to the sleeve and cylinder axes, said sleeve having intake and exhaust ports cooperating with the respective cylinder ports, said cylinder intake port having a closing edge formed of connected longitudinally spaced and laterally offset substantially horizontal edge portions, said sleeve intake port having a closing edge formed of connected longitudinally spaced and laterally offset substantially horizontal edge portions. 105
